UNITED STATES PATENT OFFICE.

JERE TURPIN, OF SAN DIEGO, CALIFORNIA.

PERPETUAL CALENDAR.

1,283,982.

Specification of Letters Patent.

Patented Nov. 5, 1918.

Application filed May 5, 1917. Serial No. 166,746.

To all whom it may concern:

Be it known that I, JERE TURPIN, am a citizen of the United States, residing at San Diego, in the county of San Diego and State 5 of California, have invented certain new and useful Improvements in Perpetual Calendars, of which the following is a specification.

This invention relates to calendars and more especially to a calendar susceptible of practical service as an everyday or current calendar and also for use when occasion demands as a perpetual calendar. Another 15 object is to produce a calendar of the character outlined, which can be embodied in practical form sufficiently small for use on a lead pencil or fountain pen. A further object is to produce a very simple, durable, compact and efficient perpetual calendar 20 which can be produced at a cost sufficiently low to make it feasible to be given away as an advertisement.

More specifically my object is to produce a perpetual calendar composed of three adjustable members, one containing years data 25 and the days of the week, another containing months data and an opening for alining a particular month with the desired year, and the third having the days of the month, 30 oponings to register with the days of the week, and a slot to expose the months data, the parts being so constructed and the data 35 so arranged that one can readily ascertain upon what day of the week a particular event did or will happen, within the scope of the calendar.

With these general objects in view, the invention consists in certain novel and peculiar features of construction and combination of parts as hereinafter described and claimed; and in order that it may be fully understood, reference is to be had to the accompanying drawing, in which:

Figure 1, represents a side elevation of a 45 perpetual-type calendar embodying my invention, the same being shown as mounted upon a lead pencil of exaggerated diameter.

Fig. 2, is a central vertical section taken on the line II—II of Fig. 1.

Fig. 3, is a horizontal section on the line III—III of Fig. 2.

Fig. 4, is a horizontal section on the line IV—IV of Fig. 1.

Fig. 5, is a view of a blank which when 5 rolled to cylindrical form constitutes the

months or intermediate cylinder of the calendar.

Fig. 6, is a similar view of a blank which when rolled to cylindrical form, constitutes the inner or years and days of the week 60 cylinder.

Before proceeding with a detailed description of the invention, it is to be understood that by the terms "cylindrical," "rotate," and the like, applicant has no intention of 65 restricting the scope of his invention to the embodiment thereof herein shown and described, as it is obvious that within the principle of construction involved, a perpetual calendar can be made in which the parts are 70 flat and have reciprocatory as distinguished from rotatable movement.

In carrying out my invention, I produce from a blank of sheet metal, celluloid, paper or other suitable material, a cylinder of 75 form and size best adapted for fitting snugly on a lead pencil, pen holder or equivalent support A. The sheet, B, is divided by vertical lines into seven columns C, on which are printed or otherwise applied the years of 80 any particular century in which the calendar is adapted for use. In the drawing the range of years shown is from 1914 to 1925 inclusive, only the last two numbers of the respective years being used, as facilitating 85 legibility. As the range of years greatly exceeds the number of vertical columns, it will be noted that the numbers indicative of particular years are arranged in a plurality of horizontal rows, two horizontal rows only 90 being shown. In the first column of the upper row, the numbers 14 to 19 inclusive appear, said numbers when the blank is in cylindrical form, appearing in the proper numerical progression, except that 16, for example, representative of a leap year, is in the second column beyond the column identified by the number 15, and said leap year column is distinctively colored,—the back ground in this case representing red. 95

Logically the years represented in the second row, run from 20 to 24 inclusive, and in this span of years two leap years occur. This leaves two vertical columns of such row blank, one before the leap year 105 20, and the other before the leap year 24, which years like the year 16 are shaded to represent red back grounds. In order to give the cylindrical calendar the fullest capacity or range, the year 1925 is shown in 110

the second row, as such year is the next in sequence to the leap year 1924, and as the first day of the year 1925 occurs on the same day of the week as the first day of the year 5 1914, the "25" is applied in the same vertical column as the year "14" but below the same. As the next year 1926 in sequence will not start on the same day as the year 1918, the blank space in the second row underlying 10 "18" cannot be utilized, so that the next range of years beginning with "26" should occur in a third horizontal row, not shown. In this connection it will be noticed that the blank B also contains in a horizontal row 15 the names of the days of the week D, and by reference to Fig. 6, it will be seen that when the blank is rolled to cylindrical form, the days of the week are vertically or longitudinally alined with the years which 20 respectively begin on such days, except that leap years are alined one day of the week ahead of the day on which they begin, the extra leap year day, not affecting January and February of the year in which it occurs 25 but affecting the following months in the same way as if the year were a common year beginning on one day of the week later than leap year really begins. By this means only the two months January and February have 30 to be especially provided for, as hereinafter stated, instead of the ten following months, as would be the case if the leap year number appears in the space upon which the year really begins. It will be noted however 35 that as the lower portion of the blank B is made of greater thickness than the upper portion so as to form an upwardly-disposed annular shoulder E, the circumferential length of the lower portion is greater 40 than that of the upper portion and consequently some of the colmuns D do not appear in direct alinement with the respective columns containing the years, as will be noted by reference to Fig. 6. In the completed device however, the columns are vertically alined, and the operator, aware of this, knows that the name of any day in row D is the first day of any year in an alined column C.

45 50 The blank F, shown in Fig. 5, is rolled to form the intermediate or months cylinder, and such cylinder fits snugly on the reduced or upper portion of the cylinder produced from blank B, and upon the shoulder E thereof, and said cylinder F, as will be seen by reference to the blank thereof, is divided by vertical lines into seven columns G of equal width, and said columns are divided by horizontal lines into three horizontal 55 60 rows, the top row containing the months "Jan." and "Feb." the second or middle row the months "Oct." "May." "Aug." "Mch." "Dec." and "July," the vertical column between the months of "Mch." and "Dec." being 65 blank. The bottom row contains all of

the thirty day months, namely, "Apr." "Jun." "Sep." and "Nov." the "Apr." column being vertically under the "July" column of the middle row, the "Jun." column being vertically under the blank column of 70 the middle row, the "Sep." column being vertically under the "Mar." column of the middle row, and the thirty day months are lined in a distinctive color,—for convenience the back grounds of said thirty day months 75 are lined to represent green.

The month of "Jan." and the month of "Feb." because affected respectively through the periodic occurrence of leap years, are applied directly on vertical lines between certain columns, the abbreviation "Jan." occurring on the vertical line between the columns in which occur the month of "Oct." and the months of "July" and "Apr." and the abbreviation "Feb." occurring on the 85 line between the columns in which occur the month of "Aug." and the months of "Mar." and "Nov." the side margins of the blank F of course coinciding when the blank is rolled to cylindrical form and therefore 90 forming but a single line. To avoid confusion or mistake in the operation of the calendar, the columns to the right of "Jan." and "Feb." are provided at H with lining representative of black, which is the color 95 in which the common years as distinguished from leap years, are printed, though it is of course obvious that any other color might be employed. Likewise the columns to the left of "Jan." and "Feb." at I, are lined 10 in a distinctive color, the color being shown as red to correspond with the red back ground on which the leap years appear. If desired the right hand half of the abbreviations "Jan." and "Feb." may be printed 11 black and the left hand half of said abbreviations be printed in red, so that when either of said months is disclosed through a slot hereinafter referred to, the two colors in which the displayed abbreviation appears, 1 will at once call to the mind of the operator the fact that if it is a common year there must be relative movement between the cylinder F and the slot referred to whereby the adjacent black background shall be 1 brought into register with said slot. On the other hand if it is a leap year, the relative adjustment mentioned will be reversed so as to bring the adjacent red back ground in registration with said slot.

The cylinder F is formed near its upper end with an outwardly projecting bead J, and above said bead with a slot K in vertical alinement with the column occupied by the month of "Oct." and to hold the intermediate or months cylinder down upon shoulder E, the upper end of the reduced portion of cylinder B, is provided with an external collar L.

As it is desirable to guard against acci- 1

dental rotation between cylinders B and F, the former is provided with seven cavities or recesses M in its outer face, the same occurring preferably between the seven years columns, and cylinder F is provided with an inwardly projecting protuberance N adapted to snap into any of the cavities or recesses M so that a positive application of force will be necessary to effect relative turning movement between said cylinders B and F, and in this connection it will be noted that the external diameter of the enlarged portion of cylinder B and cylinder F is equal so that their outer faces are flush.

15 Fitting rotatably on the enlarged portion of cylinder B and on cylinder F, and bearing at its upper end against the bead J and at its lower end against a retaining collar O secured on the lower end of the cylinder B, 20 is the outer or days of the month cylinder P, and said cylinder below the horizontal plane of the row D of the days of the week of cylinder B, is divided into seven vertical columns Q, only three of which clearly appear, and said columns are divided into five horizontal rows. In one of the said vertical columns, and progressively in the horizontal rows from the top to the bottom appears the days of the month, as follows; 1, 8, 15, 22, 25 and 29; the second column runs in the same manner 2, 9, 16, 23, and 30; the third column runs 3, 10, 17, 24, and 31; the fourth runs 4, 11, 18, and 25; the fifth, 5, 12, 19, and 26; the sixth, 6, 13, 20, and 27; and the seventh, 30 7, 14, 21, and 28, the columns between the second and seventh not being shown. In line with and at the upper end of said days of the week columns, the cylinder P is provided with seven equi-distant openings R, 35 through which may be observed the names of the days of the week appearing on the cylinder B. Vertically above the opening R in line with the days of the month column which begins with the first day of the month, is a vertical slot which in length corresponds to the length of the months columns on cylinder F. For convenience and also to avoid unnecessarily weakening the cylinder P, the slot mentioned is shown in 40 three sections S, one section in the horizontal plane of each of the rows on the months cylinder.

The 29th and 30th days of the month are distinctively colored to correspond respectively with the coloring of the leap years and the thirty day months. For convenience the back grounds for said days are lined to represent the colors mentioned.

45 As the calendar is shown and described there is a fixed relation between the column of cylinder F bearing "Oct" and the opening K. A different month might have been arranged in the relation set forth in lieu of the month of October, and the selection of 50 a different month in such relation clearly

falls within the spirit and scope of my invention.

As will be noted by reference to Fig. 1, the designations for two months appear simultaneously in the slot S, and as will be understood, slot K will simultaneously expose a vertical row of the designations of years on cylinder B. To avoid any possibility of confusion through the display of the designations of two months at the same time, a sleeve T, preferably semi-transparent, fits adjustably on the outer cylinder P, so that it may be employed to cover either one of the designations of months which are simultaneously displayed through the opening S, the one left uncovered being the one sought. A similar adjustable sleeve U is mounted on the cylinder F above the bead J thereof, and is adapted to be adjusted to uncover slot K in the horizontal plane of the row of years designations containing the particular year sought.

Assuming that it is desired to ascertain on what day of the week the first day of March, 1916, occurred, the operator grasps 90 the upper end of cylinder F and turns the pencil including the cylinder B until the leap year "16" of the years' designations on cylinder B, is displayed through the slot K.

The operator while still holding the cylinder F, then turns the outer cylinder P, until the designation for the month of March appears through the intermediate section or portion of slot S of the cylinder, it being noted that the month of November is incidentally displayed through the lower section of said slot S, and that the lining H, also appears through the uppermost section of said slot. If the sleeves T and U are employed, it will be advantageous to adjust them so as to respectively cover the month of "Nov." and the designation of the year 1922 occurring in the same column with, but below the designation of the year 1916. With the parts arranged as explained it will be apparent that as the designation "We." appears through the opening R in vertical alignment with the slot S and the column of numbers headed by the number 1, that the first day of March, 1916, occurred on Wednesday.

From the above description it will be apparent that I have produced a calendar of the perpetual type, which embodies the features of advantage enumerated as desirable 120 in the statement of the object of the invention, and while I have illustrated and described the preferred embodiment of the invention, it is to be understood that I reserve the right to make any and all changes in form, proportion and organization which properly fall within the spirit and scope of the appended claims.

I claim:

1. A perpetual calendar, comprising a 13

member having seven vertical columns on which successive years appear in horizontal rows, the leap years being spaced in the second columns ahead of those occupied by their respective preceding years; said member also bearing the names of the days of the week arranged in order, and each vertically in line with certain of the said years columns; a second member relatively adjustable to and overlapping the first member except where the same discloses the names of the days of the week, and provided with seven columns adapted for alinement with the columns of the first member and with an opening for registration with any of the years columns of said first member, said seven columns of the second member containing the names of the months in three horizontal rows, the name of a selected month being alined with the said opening; and a third member overlapping the uncovered portion of the first member and that portion of the second member containing the names of the months, and provided with a horizontal series of seven openings through which to expose the names of the days of the week, a vertical slot in alinement with one of said openings, through which to expose vertical columns containing the names of the months, and provided below the said seven openings with the days of the month in seven columns, the days appearing in numerical order with the corresponding days of the rows in vertical alinement, and with the first day of the month in vertical alinement with the said vertical slot.

2. A perpetual calendar, comprising a member having seven vertical columns on which successive years appear in horizontal rows, the leap years being spaced in the second columns ahead of those occupied by their respective preceding years; said member also bearing the names of the days of the week arranged in order, and each vertically in line with certain of the said years columns; a second member relatively adjustable to and overlapping the first member except where same discloses the names of the days of the week, and provided with seven columns adapted for alinement with the columns of the first member and with an opening for registration with any of the years columns of said first member, said seven columns of the second member containing the names of the months in three horizontal rows, the name of a selected month being alined with the said opening; one row of said second member containing only the designations of two months, "Jan." and "Feb.," the abbreviation "Jan." appearing between the columns containing the designations "Oct." and "July" and the abbreviation "Feb." occurring between the columns containing the abbreviations "Aug." and "Mar.," the columns between which said abbreviations "Jan." and "Feb." appear containing distinctive coloring to indicate common and leap years respectively, one of said rows also containing only the names of the months composed of thirty days, and distinctively colored, and a third member overlapping the uncovered portion of the first member and that portion of the second member containing the names of the months, and provided with a horizontal series of seven openings through which to expose the names of the days of the week, a vertical slot in alinement with one of said openings, through which to expose vertical columns containing the names of the months, and provided below the said seven openings with the days of the month in seven columns, the days appearing in numerical order with the corresponding days of the rows in vertical alinement, and with the first day of the month in vertical alinement with the said vertical slot, the twenty-ninth day of the

ping the uncovered portion of the first member and that portion of the second member containing the names of the months, and provided with a horizontal series of seven openings through which to expose the names of the days of the week, a vertical slot in alinement with one of said openings, through which to expose vertical columns containing the names of the months, and provided below the said seven openings with the days of the month in seven columns, the days appearing in numerical order with the corresponding days of the rows in vertical alinement, and with the first day of the month in vertical alinement with the said vertical slot.

3. A perpetual calendar, comprising a member having seven vertical columns on which successive years appear in horizontal rows, the leap years being spaced in the second columns ahead of those occupied by their respective preceding years; said member also bearing the names of the days of the week arranged in order, and each vertically in line with certain of the said years columns; a second member relatively adjustable to and overlapping the first member except where same discloses the names of the days of the week, and provided with seven columns adapted for alinement with the columns of the first member and with an opening for registration with any of the years columns of said first member, said seven columns of the second member containing the names of the months in three horizontal rows, the name of a selected month being alined with the said opening; one row of said second member containing only the designations of two months, "Jan." and "Feb.," the abbreviation "Jan." appearing between the columns containing the designations "Oct." and "July" and the abbreviation "Feb." occurring between the columns containing the abbreviations "Aug." and "Mar.," the columns between which said abbreviations "Jan." and "Feb." appear containing distinctive coloring to indicate common and leap years respectively, one of said rows also containing only the names of the months composed of thirty days, and distinctively colored, and a third member overlapping the uncovered portion of the first member and that portion of the second member containing the names of the months, and provided with a horizontal series of seven openings through which to expose the names of the days of the week, a vertical slot in alinement with one of said openings, through which to expose vertical columns containing the names of the months, and provided below the said seven openings with the days of the month in seven columns, the days appearing in numerical order with the corresponding days of the rows in vertical alinement, and with the first day of the month in vertical alinement with the said vertical slot, the twenty-ninth day of the

days of the month being distinctly colored to correspond with the color indicative of leap years and the thirtieth day of the days of the month being colored to correspond 5 with the coloring of the thirty day months.

4. A calendar comprising a cylindrical member having an upwardly facing annular shoulder and provided with designations of the days of the week in a horizontal row 10 and with designations of the years in other horizontal rows, and with a series of seven equi-spaced recesses; a second cylinder fitting rotatably on the first cylinder and resting on the shoulder thereof and provided 15 with a slot for exposing one year's designation at a time, of each horizontal row thereof, and provided with three rows of designations of months, one of said designations of months being in line with said slot, and 20 provided also with a protuberance for engaging either of said recesses of the first cylinder to prevent accidental relative rotation of said cylinders, said second cylinder also having an external bead below said 25 slot, a collar secured on the first cylinder and abutting the upper end of said second cylinder, a third cylinder fitting rotatably on the first and second cylinders and at its upper end abutting said bead and provided with 30 designations of the days of the month arranged in seven vertical columns, and with a vertical slot for disclosing the designations of the months, and also provided between said 35 slot and said designations of the days of the month with seven openings for exposing simultaneously the designations of the days of the week, a collar secured on the first-named cylinder and abutting the lower end of the third cylinder, an adjustable collar on the third cylinder for covering either 40 of the rows of designations of the months on the second cylinder, and a collar fitting on the second cylinder and adjustable to cover the designations of the years on the first cylinder displayed through the said 45 slot of the second cylinder, except the particular year sought.

In testimony whereof, I affix my signature, in the presence of two witnesses.

JERE TURPIN.

Witnesses:

F. D. BRUTON,
P. A. WHITACRE.

Copies of this patent may be obtained for five cents each, by addressing the "Commissioner of Patents, Washington, D. C."

with designations of the years in other 45 horizontal rows, and with a series of seven equi-spaced recesses; a second cylinder fitting rotatably on the first cylinder and resting on the shoulder thereof and provided with a slot for exposing one year's designation 50 at a time, of each horizontal row thereof, and provided with three rows of designations of months, one of said designations of months being in line with said slot, and provided also with a protuberance for 55 engaging either of said recesses of the first cylinder to prevent accidental relative rotation of said cylinders, said second cylinder also having an external bead below said slot, a collar secured on the first cylinder and abutting the upper end of said second cylinder, a third cylinder fitting rotatably on the first and second cylinders and at its upper end 60 abutting said bead and provided with designations of the days of the month arranged 65 in seven vertical columns, and with a vertical slot for disclosing the designations of the months, and also provided between said slot and said designations of the days of the month with seven openings for exposing 70 simultaneously the designations of the days of the week, a collar secured on the first-named cylinder and abutting the lower end of the third cylinder, an adjustable collar on the third cylinder for covering either 75 of the rows of designations of the months on the second cylinder, and a collar fitting on the second cylinder and adjustable to cover the designations of the years on the first cylinder displayed through the said 80 slot of the second cylinder, except the particular year sought.
